UNITED STATES PATENT OFFICE

MIGUEL ENRIQUE GUERMONT, OF LONDON, ENGLAND, ASSIGNOR TO S. I. A. M. LIMITED, OF LONDON, ENGLAND, A CORPORATION OF GREAT BRITAIN

APPARATUS FOR DELIVERING MEASURED QUANTITIES OF LIQUIDS

Application filed June 7, 1929, Serial No. 369,156, and in Great Britain June 28, 1928.

The present invention relates to improvements in those discharge mechanisms for petrol pumps and like devices which are provided with a fixed or movable overflow pipe placed inside a liquid container or reservoir, in which it is desired to establish an exact level of the liquid corresponding to a determined quantity of the liquid to be discharged from the said container and particularly the 10 class of mechanism in such a device in which the delivery valve is locked when the valve is closed and only unlocked by the overflow of the liquid through the overflow pipe when more than the predetermined quantity of liquid has been measured into the container thus ensuring that short measure cannot be given. Bucket valves controlling lock bars co-acting spring controlled release bars have been suggested in such a pump.

20 The present invention provides in this class of discharge mechanism for petrol pumps a butterfly control valve which is mounted in the overflow pipe and co-acts with a trip adapted to release a stop when the 25 liquid overflows into the pipe, said stop engaging with a shoulder on a member connected to the operating mechanism of the discharge valve when the stop is locked by the trip and being clear of said shoulder when 30 the stop is released by the trip and moved to the unlocked position.

A mechanism designed with this object in view is illustrated by way of example in the accompanying drawings, in which—

35 Figure 1 shows a diagrammatic view of the mechanism with the control valve in the overflow pipe in the closed position and the discharge valve locked, and

40 Figures 2 and 3 show detail views of two positions of an inclined member integral with a sliding rod connected to the delivery handle and a stop co-acting with said inclined member projecting from a spring controlled rod adapted to be released by the control valve.

In the mechanism shown in the drawings, a butterfly valve 1 is mounted in the overflow pipe 2 of the liquid container 3, the mouth of which pipe is set in the container to draw off any liquid above such a level as to give

the desired measure of liquid when the delivery valve is opened. The valve 1 is integral with the pivoted arm 4 which arm is provided with an adjustable counterweight 5 and with a trip 6 shown in engagement with the lug 7 on the releasing and locking rod 8. This rod is adapted to slide in the supporting guide 16 and is controlled by the spring 29 tending to move said rod to the right when the trip 6 on the valve arm 4 is moved out of engagement with the lug 7 thus moving a stop 9 laterally projecting from the said rod out of engagement with a shoulder 10 on a vertical rod 11 connected by the pin 12 with the handle 13 adapted to operate the discharge valve 20 of the container 3. The shoulder 10 is integral with an inclined member 15. When the rod 8 is released it is moved by its controlling spring 29 to a position in which the stop 9 is to the right of the lower edge of the inclined member and the lug 17 at the end of said rod is in engagement with the compression spring 18. When the stop 9 is out of register with the shoulder 10 the operator can pull down the handle 13 against the influence 70 of the spring 19 if such a spring is employed and thus open the discharge valve 20 of the container 3. The downward movement of the handle 13 to open the delivery valve at once brings the position of the inclined member 15 in relation to the stop 9 to that shown in Figure 2 and the continued downward movement of the inclined member moves said stop further to the right and thus presses the lug 17 at the end of the carrying rod 8 against 75 the compression spring 18. When the position of the parts are such that the stop 9 can pass over the upper edge of the inclined member 15 the rod 8 is moved to the left by the compression spring 18 to a position in which the stop is in front of the inner surface of the inclined plate 15. The upward movement of the delivery handle 13 to close the delivery valve after the desired quantity of liquid has

80 been delivered to the consumer from the container at once brings the position of the inclined member 15 in relation to the stop 9 to that shown in Figure 3 and the continued upward movement of the delivery handle moves the stop 9 and with it the carrying rod 85 90 95 100

8 to the left until the parts reach the position shown in Figure 1 when the inclined surfaces of the lug 7 at the free end of the carrying rod 8 and the trip 6 on the weighted valve arm 4 engage and the trip rides over the lug 7 and then assumes the position shown holding the rod in the position in which the said stop 9 is under the shoulder 10 on the vertical rod connected to the delivery valve.

10 What I claim is:

1. A discharge mechanism for petrol pumps and like devices comprising in combination a liquid measuring container, a discharge valve for said container and operating mechanism therefor, an overflow pipe within said container adapted to draw off the excess liquid fed into said container, a butterfly control valve mounted in said overflow pipe, a trip adapted to be actuated by said butterfly valve when the liquid overflows into said pipe, a movable member connected to the operating mechanism of the discharge valve, a shoulder on said member and a stop adapted to register with the shoulder when said stop is locked by the trip and to be moved clear of said shoulder to release the operating mechanism of the discharge valve when said stop is released by the trip.
2. A discharge mechanism for petrol pumps and like devices comprising in combination a liquid measuring container, a discharge valve for said container and operating mechanism therefor, an overflow pipe within said container adapted to draw off the excess liquid fed into said container, a butterfly control valve mounted in said overflow pipe, a trip adapted to be actuated by said butterfly valve when the liquid overflows into said pipe, a movable member connected to the operating mechanism of the discharge valve, a shoulder on said member, a stop adapted to register with the shoulder when said stop is locked by the trip and to be moved clear of said shoulder to release the operating mechanism of the discharge valve when said stop is released by the trip.
3. A discharge mechanism for petrol pumps and like devices comprising in combination a liquid measuring container, a discharge valve for said container and operating mechanism therefor, an overflow pipe within said container adapted to draw off the excess liquid fed into said container, a butterfly control valve mounted in said overflow pipe, a trip adapted to be actuated by said butterfly valve when the liquid overflows into said pipe, a movable member connected to the operating mechanism of the discharge valve, a shoulder on said member, a stop adapted to register with the shoulder when said stop is locked by the trip and to be moved clear of said shoulder to release the operating mechanism of the discharge valve when said stop is released by the trip.

be moved clear of said shoulder to release the operating mechanism of the discharge valve when said stop is released by the trip, an inclined returning member integral with said shoulder adapted to engage with the stop when the latter is released and moved out of engagement with the shoulder and a compression spring adapted to be engaged by the stop when the latter is moved outwards by the inclined member on the opening movement of the discharge valve mechanism.

4. A discharge mechanism for petrol pumps and like devices comprising in combination a liquid measuring container, a discharge valve for said container and operating mechanism therefor, an overflow pipe within said container adapted to draw off the excess liquid fed into said container, a butterfly control valve mounted in said overflow pipe, a pivoted arm integral with said valve carrying an adjustable counter-weight, a trip projecting from said arm adapted to be actuated with said arm by said butterfly valve when the liquid overflows into said pipe, a movable member connected to the operating mechanism of the discharge valve, a shoulder on said member and a stop adapted to register with the shoulder when said stop is locked by the trip and to be moved clear of said shoulder to release the operating mechanism of the discharge valve when said stop is released by the trip.

5. A discharge mechanism for petrol pumps and like devices comprising in combination a liquid measuring container, a discharge valve for said container and operating mechanism therefor, an overflow pipe within said container adapted to draw off the excess liquid fed into said container, a butterfly control valve mounted in said overflow pipe, a trip adapted to be actuated by said butterfly valve when the liquid overflows into said pipe, a vertical rod connected to the operating mechanism of the discharge valve, a shoulder on said rod and a stop adapted to register with the shoulder when said stop is locked by the trip and to be moved clear of said shoulder to release the operating mechanism of the discharge valve when said stop is released by the trip.

6. A discharge mechanism for petrol pumps and like devices comprising in combination a liquid measuring container, a discharge valve for said container and operating mechanism therefor, an overflow pipe within said container adapted to draw off the excess liquid fed into said container, a butterfly control valve mounted in said overflow pipe, a trip adapted to be actuated by said butterfly valve when the liquid overflows into said pipe, a movable member connected to the operating mechanism of the discharge valve, a shoulder on said member and a spring controlled bar carrying a laterally projecting stop adapted to register with the

shoulder when said stop is locked by the trip and to be moved clear of said shoulder to release the operating mechanism of the discharge valve when said stop is released by the trip.

5 7. A discharge mechanism for petrol pumps and like devices comprising in combination a liquid measuring container, a discharge valve for said container and operating mechanism therefor, an overflow pipe within said container adapted to draw off the excess liquid fed into said container, a butterfly control valve mounted in said overflow pipe, a pivoted arm integral with said 10 valve carrying an adjustable counter-weight, a trip projecting from said arm adapted to be actuated with said arm by said butterfly valve when the liquid overflows into said pipe, a vertical rod connected to the operating 15 mechanism of the discharge valve, a shoulder on said rod and a spring controlled bar carrying a laterally projecting stop adapted to register with the shoulder when said stop is locked by the trip and to be moved clear of 20 said shoulder to release the operating mechanism of the discharge valve when said stop is released by the trip.

8. A discharge mechanism for petrol pumps and like devices comprising in combination a liquid measuring container, a discharge valve for said container and operating mechanism therefor, an overflow pipe within said container adapted to draw off the excess liquid fed into said container, a butterfly control valve mounted in said overflow pipe, a trip adapted to be actuated by said butterfly valve when the liquid overflows into said pipe, a movable member connected to the operating mechanism of the discharge 30 valve, a shoulder on said member, a stop adapted to register with the shoulder when said stop is locked by the trip and to be moved clear of said shoulder to release the operating mechanism of the discharge valve 35 when said stop is released by the trip, an inclined returning member integral with said shoulder adapted to engage with the stop when the latter is released and moved out of engagement with the shoulder and a compression spring positioned to be engaged by the stop when the latter is moved outwards by the outer surface of the inclined member on the opening movement of the discharge valve mechanism and adapted to return the 40 stop to a position to be engaged by the inner surface of the inclined member on the closing movement of the said discharge valve mechanism.

In testimony whereof I have signed my 45 name to this specification.

MIGUEL ENRIQUE GUERMONT.
